REMOTE CONTROLLING APPARATUS

Lester E. Spray, Wilkinsburg, Pa., assignor to The
Union Switch & Signal Company, Swissvale,
Pa., a corporation of Pennsylvania

Application May 19, 1928, Serial No. 279,062

109 Claims. (Cl. 246—3)

My invention relates to remote controlling apparatus, and particularly to apparatus for safely controlling traffic governing devices, such as railway switches and signals, from a distant point.

5 I will describe three forms of apparatus embodying my invention, and will then point out the novel features thereof in claims.

In the accompanying drawings, Fig. 1 is a diagrammatic view showing one form of remote controlling apparatus, embodying my invention, as applied to a single switch and the signals for governing traffic over such single switch. Fig. 2 is a fragmentary view showing a modified form of the apparatus of Fig. 1, including a derail in conjunction with the switch shown in Fig. 1, and also embodying my invention. Fig. 3 is a fragmentary view showing, in turn, a modified form of the apparatus of Fig. 2, particularly for the control of switch indication means, and also embodying my invention.

20 Similar reference characters refer to similar parts in each of the three views.

Referring first to Fig. 1, reference characters 1 and 1^a designate the track rails of a stretch X of railway track connected, by means of a switch F , with a passing siding Y . The switch F is controlled by a motor M , which in the form here shown comprises an armature 128 and a field 134 .

The track rails 1 and 1^a of stretch X are divided, 30 by means of insulated joints 2 , into a plurality of track sections $A—B$, $B—C$ and $C—D$, track section $B—C$ containing the switch F . A portion of track rail 1^b of siding Y , adjacent the switch F , is insulated from the rest of siding Y , and from stretch X , by other insulated joints 2 to form section $E—C^1$, and the rail of section $E—C^1$ is electrically connected, in series, with that portion of rail 1^a which is included in section $B—C$. The portion of the other rail of siding Y , which is opposite to section $E—C^1$, is not insulated from rail 1 of section $B—C$ and is therefore in multiple with rail 1 between points E and C . Sections $E—C^1$ and $B—C$ will therefore be referred to hereinafter, collectively, as section $B—C—C^1—E$. Each of 35 the track sections $A—B$, $C—D$, and $B—C—C^1—E$ is provided with a track relay, designated by the reference character G with a suitable distinguishing exponent and connected across the rails adjacent one end of the corresponding section.

50 Track circuit current is supplied to the rails of each section by a battery 3 , connected across the rails adjacent the opposite end of such section.

Eastbound traffic, that is, traffic moving from 55 left to right, is governed by signals S^1 and S^2 ,

which are mounted on a common mast 213 , and which as here shown are of the semaphore type. Westbound traffic, that is, traffic moving from right to left, from siding Y , over switch F reversed, is governed by signal S^4 . Westbound traffic moving on track X , over switch F normal, is controlled by signal S^3 .

The switch F and signals S^1 , S^2 , S^3 , and S^4 are controlled, in part, by a neutral relay designated by the reference character H , and, in part, 10 by a polarized relay L responsive only to current of a greater magnitude than that required to operate relay H . Relays H and L are, in turn, controlled by a manually operable lever V having six resting positions designated respectively by 15 the reference characters p , n , b , d , r and t . Lever V is equipped with seven contacts 5 , 206 , 118 , 157 , 138 , 234 , and 162 . Contacts 5 and 138 are each closed when lever V is in its r or t positions or at any point intermediate between these 20 two positions, contacts 206 and 234 are each closed while lever V is in its n or p positions or at any point intermediate thereto, contact 118 is closed while lever V is in its n or r position or at any point intermediate thereto, and contacts 157 and 25 162 are closed while lever V is in its b or its d positions or at any point intermediate thereto. Lever V may be one of a plurality of such levers grouped together at some central control point, such as a train dispatcher's office.

30 Associated with, and controlled in part by, lever V at the control point, is an indication relay I .

Associated with the control of relays H , I and L , are two asymmetric units designated Z^1 and Z^2 , respectively, each of which units may be similar 35 to those disclosed and claimed in Letters Patent of the United States, No. 1,640,335, granted to L. O. Grondahl, August 23, 1927.

A slow acting signal stick relay T is so controlled by lever V and relay I , and in turn so 40 controls relays H and L as to effect the non-stick operation of signals S^1 , S^2 , S^3 and S^4 while lever V is in its n or r positions, and to effect the stick operation of these signals while lever V is in its p or t positions.

45 The reference character W designates a clock-work release of the well known normally latched type. From the instant that contact $12—12^a$ opens, when release W is unlatched, a measured interval of time elapses before contact $12—12^b$ 50 closes.

Associated with switch F is a switch locking mechanism, not shown but of a well known type, also operated by motor M so as to lock switch F in its normal or reverse positions. Also associ- 55

ated with switch F is a circuit controller a , comprising seven contacts 19, 173, 215, 187, 95, 82, and 132. Contact 19 is arranged to be closed at all times, except for a brief period while the switch locking mechanism is unlocking switch F and for another brief period while the switch locking mechanism is locking switch F; contacts 215 and 95 are closed only while switch F is locked in its normal position; contact 173 is closed only while switch F is locked in its reverse position; contacts 187 and 82 are closed while switch F is locked in either its normal or its reverse position, but are open at all other times; and contact 132 engages a segment 132^a at all times except while switch F is locked in its reverse position and similarly engages a segment 132^b at all times except while switch F is locked in its normal position.

Associated with track relay G¹, and controlled by a front contact and a back contact thereof, is a repeater relay g¹. Similarly associated with track relay G², and similarly controlled by a front and a back contact thereof, is a repeater relay g².

Associated with signals S¹, S², S³ and S⁴, and controlled by contacts 62, 64, 60 and 58, which are operated by these signals, respectively, and each of which contacts is closed only while the corresponding signal indicates "stop", is a signal back locking relay N. It is evident that relay N will be energized only while all of these signals are indicating "stop", and that it will become deenergized when the arm of any one of these signals moves away from its "stop" position.

Controlled in part by track relays G¹, G² and G³ and repeater relays g¹ and g², and in part by contacts of circuit controller a , is a directional approach stick relay J, the circuits for which are so arranged that this relay is normally energized, but will become de-energized by an approaching train entering sections A—B or C—D, and will again become energized when such train enters section B—C—C¹—E, and will continue energized while such train is moving away from switch F.

An approach or stick locking relay P is in turn controlled, in part, by relay J in conjunction with a contact of circuit controller a , and is also controlled, in part, by back locking relay N, by track relay G², and by control relay L. The circuits are so arranged that relay P will become de-energized as soon as either signal S² or S⁴ is cleared for a move over switch F reversed, and relay P can then, while switch F is reversed, again become energized only by the deenergization of relay G², as by a train entering section B—C—C¹—E, or by the operation of clockwork release W to supply current in reverse direction for causing relay L to close its reverse contacts. When either signal S¹ or S³ is cleared for a move on track X over switch F normal, relay P will not become de-energized until an approaching train de-energizes relay G¹ or relay G³.

A polarized relay R controls the operating current supplied to switch motor M. The direction of energization of relay R is in turn controlled by relays H and L.

At the control point, indicator lamp e, at such times as lever V is in its p , n , r , or t positions, indicates, by means of a flash, the approach of a train in sections A—B or B—C. While lever V is in its b or d positions, lamp e will be lighted continuously from the time an approaching train enters section A—B or C—D. Lamp e also provides a continuous indication when a train occupies section B—C—C¹—E while lever V is in its p , n , r or t positions. During the operation of switch F, lamp e provides a first single flash at

the unlocking of switch F, and a second similar flash at the locking of switch F upon completion of its movement.

In Fig. 2, changes in, and additions to, parts of the apparatus of Fig. 1 are shown as required for controlling and indicating the operation of a derail F^e in conjunction with the switch and signals shown in Fig. 1. Other parts of Fig. 1, which are not shown in Fig. 2, are to be understood as operating in conjunction with the parts shown in Fig. 10, similarly to Fig. 1. The operating current for motor M^e of derail F^e is controlled similarly to that for motor M of switch F, by a polarized relay R^e which is in turn controlled by relay R. Instead of contact 19, shown in circuit controller a of Fig. 1, in the circuit of relays L, H, and I, contact 241 of circuit controller a and contact 239 of circuit controller a^e are substituted in Fig. 2. Contacts 241 and 239 are closed only while switch F and derail F^e, respectively, are locked in their normal or reverse positions.

A primary indication relay f is energized only when both contacts 241 and 239 are closed while both switch F and derail F^e are locked normal, or while both switch F and derail F^e are locked reversed. Associated with primary indication relay f, and controlled by a front contact thereof, is a slow acting secondary indication relay K. A front contact of each of these two relays is included in series with each other in the circuit of relays L, H and I. A branch path, around these two front contacts in the circuit of relays L, H and I, includes a back contact of each of these two relays. Indication relay I is so constructed as to be responsive to the open circuit interval between the opening of contact 250, at its front point 250^a, and the closing of contact 252, at its back point 252^b, as well as to the open circuit interval between the opening of contact 250, at its back point 250^b, and the closing of contact 252, at its front point 252^a.

Fig. 3 differs from Fig. 2 only in the control of primary indication relay f, which in Fig. 3 is normally deenergized and in Fig. 2 is normally energized. In Fig. 3, circuit controllers a and a^e of switch F and derail F^e, respectively, control relay f by means of contacts 261 and 267 which are closed at all times except while switch F and derail F^e, respectively, are locked in their normal or reverse positions, whereas, contacts 241 and 239, in Fig. 2, are closed only while the switch F and derail F^e are locked in their normal or reverse positions.

Having thus described, in general, the arrangement and location of the various constituent parts comprising my invention, I will now proceed to explain the operation of the apparatus.

As shown in Fig. 1, lever V is in its b position, switch F is normal, all track sections are clear, and all track relays are energized. Since track relay G¹ is energized, repeater relay g¹ is also energized by a circuit including battery Q¹, wires 31, 46 and 47, contact 48^a—48 of relay G¹, wire 49, winding of relay g¹, and wires 50, 51 and 52 back to battery Q¹. Since track relay G³ is energized, relay g³ is also energized, by a circuit controlled by contact 53^a—53 of relay G³, in like manner as relay g¹ is controlled by contact 48^a—48 of relay G¹.

With lever V in its b position, relays H and L are de-energized, and signals S¹, S², S³, and S⁴ are at "stop". Since all signals are at "stop", signal back locking relay N is energized by a circuit including battery Q¹, wires 54, 55, 56, and 57, circuit controller contact 58 of signal S⁴, wire 75

- 59, contact 60 of signal S³, wire 61, contact 62 of signal S¹, wire 63, contact 64 of signal S², wire 65, winding of relay N, and wires 66, 67, 68, 70 and 45 back to battery Q¹.
- 5 With approach track sections A—B and C—D unoccupied, therefore, and relays G¹ and G³ energized, a pick-up circuit of directional approach stick relay J is closed through battery Q¹, wires 31, 46 and 71, contact 72 of relay G¹, wire 73, 10 contact 74 of relay G³, wires 75 and 76, winding of relay J, and wires 77, 68, 70 and 45, back to battery Q¹. A stick circuit of relay J is also closed through battery Q¹, wires 54, 78, 79 and 81, contact 82—82^a of circuit controller a, wires 83 and 15 84, contact 85 of relay G³, wire 86, contact 87 of relay G¹, wires 88 and 89, contact 90 of relay G², wire 91, contact 92 of relay J, wire 93, winding of relay J, and wires 77, 68, 70 and 45 back to battery Q¹.
- 20 Since switch F is normal and relay J is energized, a pick-up circuit of approach and stick relay P is closed through battery Q¹, wires 54, 78, 79, 81 and 94, contact 95 of circuit controller a, wire 96, contact 97 of relay J, wire 98, winding 25 of relay P, and wires 99, 70 and 45 back to battery Q¹. A stick circuit of relay P is also closed, through contact 101 of relay N, and includes battery Q¹, wires 54, 78 and 100, contact 101, wire 102, contact 103 of relay P, wires 104 and 204, 30 winding of relay P, and wires 99, 70 and 45 back to battery Q¹.
- With relays H and L de-energized, and relays P, N and G² energized, current is supplied to a stick circuit of relay R from battery Q², through 35 contact 107—107 of relay R, wires 108, 109, 110 and 111, contact 112^b—112 of relay H, contact 40^b—40 of relay L, wire 39, contact 38^a—38 of relay G², wire 37, contact 36^a—36 of relay P, wire 35, contact 34^a—34 of relay N, wire 33, winding 40 of relay R, and wires 32 and 31 back to battery Q².
- With lever V in its b position, the pick-up circuit of relay T is closed, through contact 118 of lever V, and includes battery Q⁴, wires 114, 115, 116 and 117, contact 118, wire 119, winding of 45 relay T, and wires 121, 122 and 30, back to battery Q⁴. Relay T is therefore energized. On account of the approach track relays G¹ and G³ being energized, indicator lamp e is unlighted. As shown, release W is latched in its normal 50 position.
- I will assume that the dispatcher now wishes to reverse switch F, to permit traffic to move from track X to siding Y. He therefore moves lever V to its r position, causing current to be supplied by batteries Q⁴ and Q⁵ in series, to relays L, H and I in the normal direction, and of sufficient magnitude to operate relay L as well as relays H and I. Current then flows from batteries Q⁴ and Q⁵ in series, through wire 4, contact 55 5 of lever V, wires 6 and 7, contact 8 of relay T, wires 9 and 10, winding of relay I, wire 11, contact 12^a—12 of release W, wire 13, an adjustable resistance 14, wire 15, contact 16 of relay G¹, wires 17 and 18, contact 19 of circuit controller a, wires 20 and 21, contact 22 of relay G³, wires 23 and 24, asymmetric unit Z², wire 25, contact 26 of relay G², wire 27, winding of relay H, wire 28, winding of relay L, and wires 29 and 30 back to battery Q⁴. Relay L, upon closing its 60 contact 40 at front point 40^a while its normal contact 42 is closed, completes the reverse pick-up circuit of relay R, and current therefore now flows from battery Q¹, through wires 31 and 32, winding of relay R, wire 33, contact 34—34^a of relay N, wire 35, contact 36—36^a of relay P, wire 37, contact 38—38^a of relay G², wire 39, contact 40—40^b of relay L, contact 112—112^b of relay H, wires 111, 110, 109 and 108, contact 107—107^b of relay R, and wires 148, 70 and 45 back to battery Q¹.
- If now, an approaching train de-energizes relay G¹, contact 48—48^a will open, thus breaking the pick-up circuit of relay g¹, and contact 48—48^b will then close and complete a shunt circuit for 70 relay g¹, including contact 48—48^b, wire 49, winding of relay g¹, and wires 50, 51 and 149. By means of this shunt circuit, relay g¹ is caused to be slow in opening its front contacts and closing its back contacts. Relay G¹ upon becoming de- 75

energized, opens its contact 12 in the pick-up circuit previously traced for relay J, and also opens its contact 87 in the stick circuits previously traced for relay J. Relay J, thus being de-energized, closes its back contact 152 which completes a circuit, in the reverse direction, through relays L and I of sufficient magnitude to operate relay I but not relay L. Current flows from battery Q³, through wires 30 and 29, winding of relay L, wires 28, 150 and 151, contact 152 of relay J, wires 153 and 154, asymmetric unit Z¹, wire 155, contact 22 of relay G³, wires 21 and 20, contact 19 of circuit controller a, wires 18 and 17, contact 16 of relay G¹, wire 15, adjustable resistance 14, wire 13, contact 12-12^a of release W, wire 11, winding of relay I, wires 10 and 156, contact 157 of lever V, and wires 158 and 159 back to battery Q³. Relay I then closes its contact 141-141^a, thus causing lamp e to become lighted by current flowing from battery Q⁴, through wires 114, 115, 116, 136, 160 and 161, contact 162 of lever V, wire 163, contact 141^a-141 of relay I, wire 142, contact 143 of release W, wire 144, filament of lamp e, and wires 145, 122 and 30 back to battery Q⁴.

Assuming that it has been some time since the despatcher has reversed switch F, and that in the meantime the despatcher has forgotten the position to which he last operated switch F, it is convenient that he have some means of determining the position of switch F. Such means is provided by the position of lever V which is now in the *d* position, indicating that the last previous movement of switch F was to its reverse position. Similarly, for operations of switch F to the normal position, lever V is returned to the *b* position if it is desired to hold all signals at "stop". Lever V, then being in its *b* position, indicates that the last previous movement of switch F was to its normal position. Similarly, lever V, when left in its *n* or *p* positions, indicates that switch F is in its normal position, and lever V, when left in its *r* or *t* positions, indicates that switch F is in its reverse position.

If, upon the completion of an operation of switch F to its reverse position, the despatcher desires signals S² and S⁴ to go to "clear" and to be provided with non-stick operation, he permits lever V to remain in its *r* position. Operating current is now supplied to signal S² from battery Q¹, through wires 54, 78, 79 and 164, contact 165 of relay G², wire 166, contact 167-167^b of relay R, wire 168, contact 169 of relay L, wire 170, contact 171 of relay L, wire 172, contact 173 of circuit controller a, wires 174 and 175, operating mechanism of signal S², and wires 176, 51 and 52 back to battery Q¹. The operating current for signal S⁴ flows from battery Q¹, through the circuit just traced for the operating current of signal S², as far as wire 174, thence through contact 177 of relay g¹, wire 178, operating mechanism of signal S⁴, and wires 179, 180, 181, 44 and 45 back to battery Q¹. Upon the clearing of signals S² and S⁴, contacts 64 and 58 operated by these signals, respectively, are opened and interrupt the circuit for relay N, which then opens its contact 101 in the stick circuit of relay P, thus de-energizing relay P. Relay N, upon becoming de-energized, also opens the reverse pick-up circuit of relay R at contact 34-34^a and by contact 70 34-34^b, closes another reverse stick circuit of relay R, through battery Q¹, wires 31 and 32, winding of relay R, wire 33, contact 34-34^b, wire 108, contact 107-107^b of relay R, and wires 148, 70 and 45 back to battery Q¹.

If, now, while lever V is in its *r* position, an

approaching train de-energizes relay G¹, contact 16 of relay G¹ opens, thus breaking the circuit through relays L, H and I until back contact 183 of relay g¹ closes a branch path, including contact 183 and wire 182, around contact 16. During this interval, relay I drops, causing lamp e to become lighted by the circuit previously traced through contact 141^b-141. Relay G¹, upon becoming de-energized, also causes relay J to become de-energized as previously described.

As the train proceeds past signal S² and enters section B-C-C¹-E, relay G² becomes de-energized, thus opening the operating circuits of signals S² and S⁴ at contact 165 and causing these two signals to go to "stop". At the same time, relay G² opens the circuit of relays L, H and I at its contact 26, thus causing these three relays to become de-energized. Relay I, upon becoming de-energized, again closes its back contact 141-141^b, and so completes the circuit for lamp e, which now becomes lighted as before. Lamp e will now continue lighted as long as the train occupies section B-C-C¹-E, or until the despatcher changes the position of lever V. Relay G², upon becoming de-energized, closes its back contact 191, thereby completing a pick-up circuit for relay J, from battery Q¹, through wires 54, 78, 79, 81, 94 and 186, contact 187-187^b of circuit controller a, wire 188, contact 189^b-189 of relay g¹, wire 190, contact 191 of relay G², wires 192 and 176, winding of relay J, and wires 77, 68, 70 and 45 back to battery Q¹. At the same time, relay G² completes a pick-up circuit for relay P, through contact 194, and relay P now becomes energized by current flowing from battery Q¹, through wires 54, 78, 79, 81 and 94, contact 194 of relay G², wires 195 and 98, winding of relay P, and wires 99, 70 and 45 back to battery Q¹. The arms of signals S² and S⁴, upon returning to the stop position, again close the circuit of relay N, at contacts 64 and 58, respectively, and relay N thereupon opens its contact 34-34^b in a stick circuit previously traced for relay R but completes another stick circuit for relay R, through contact 34-34^a and contact 38-38^b of relay G², and including battery Q¹, wires 31 and 32, winding of relay R, wire 33, contact 34-34^a of relay N, wire 35, contact 36-36^a of relay P, wire 37, contact 38-38^b of relay G², wires 185, 109 and 108, contact 107-107^b of relay R, and wires 148, 70 and 45 back to battery Q¹. As the train leaves section B-C-C¹-E, relay G² again becomes energized, closing the circuit of relays L, H and I and causing signals S² and S⁴ to again display the clear indication, by means of operating circuits previously traced, and without further action on the part of the despatcher. Relay G², upon becoming energized, opens the pick-up circuit of relay P through contact 194, and relay N, upon becoming de-energized when signals S² and S⁴ again display the clear indication, opens the stick circuit of relay P through contact 101, and relay P is therefore de-energized. Relay J, however, continues energized, since its pick-up circuit is closed through contacts 72 and 74 of relays G¹ and G³, respectively, and its stick circuit is again closed through contact 82-82^b of circuit controller a.

If, on the other hand, upon the completion of the operation of switch F to its reverse position, the despatcher desires that signals S² and S⁴ shall indicate "clear" and be provided with stick operation, he will move lever V to its *t* position, thereby opening the pick-up circuit previously traced for relay T through contact 118 of lever V. Relay T, however continues energized through

- its stick circuit which includes battery Q⁴, wires 114, 115 and 229, contact 230 of relay I, wire 231, contact 232 of relay T, winding of relay T, and wires 121, 122 and 30 to battery Q⁴. Current will 5 now continue to flow through the windings of relays L, H and I as before, and signals S² and S⁴ will clear. If, now, a train approaches and de-energizes relay G¹, the momentary approach indication is displayed by lamp e as when lever V 10 is in its *r* position. Lamp e also becomes lighted, as before, when a train enters section B—C—C¹—E. Relay T, being slow acting, does not open its front contacts within the brief period of time during which relay I is de-energized as 15 an approaching train enters section A—B, but does become de-energized while the train is moving through section B—C—C¹—E and causing relay I to be de-energized for a longer period. As the train leaves section B—C—C¹—E, relay G² 20 becomes energized, closing its contact 26 in the circuit of relays L, H and I, which circuit, however, continues open at contact 8 of relay T, and cannot again become closed until lever V is returned to its *r* position and thus causes relay T 25 to again become energized. It is thus clear that after a train enters section B—C—C¹—E while lever V is in its *t* position, action of the despatcher is required, to move lever V, before signals S² and S⁴ will again display the clear indication. 30 If, after switch F has been reversed and signals S² and S⁴ have cleared, the despatcher should desire to return switch F to its normal position before a train enters section B—C—C¹—E, he will first move lever V to its *n* position. Thereupon, 35 relay L opens its front contact 169, breaking the operating circuits of signals S² and S⁴, the arms of which then move to the "stop" position and close contacts 64 and 58, respectively, in the circuit of relay N. Relay N, thus becoming energized, opens the reverse stick circuit, of relay R, which passes through contact 34—34^b of relay N, but, through contact 34—34^a, relay N now completes a stick circuit for relay R through contact 36—36^b of relay P, this stick circuit including 40 battery Q¹, wires 31 and 32, winding of relay R, wire 33, contact 34—34^a, wire 35, contact 36—36^b, wires 110, 109 and 108, contact 107—107^b of relay R, and wires 148, 78 and 45 back to battery Q¹. In order to open this stick circuit and complete the 45 normal pick-up circuit for relay R, relay P must be energized. While switch F is reversed and relay G² is energized, relay P can become energized only by its pick-up circuit which passes through front contact 200 and reverse contact 202 50 of relay L. In order to energize relay L in its reverse direction, release W must close its contact 12—12^b. Accordingly, the despatcher unlatches release W which thereupon opens its contact 12—12^a and thereby breaks the circuit of relays L, H and I. At the same time, release W opens its contact 143 55 in the lighting circuit of lamp e, thus preventing the lighting of lamp e until release W has again been latched in its normal position. Release W, after a measured interval of time, closes its contact 12—12^b and current is then supplied in reverse direction to relay L, from battery Q³, through wires 30 and 29, winding of relay L, wires 28, 150 and 196, contact 197 of relay P, wire 154, asymmetric unit Z¹, wire 155, contact 22 of relay G³, wires 21 and 20, contact 19 of circuit controller a, wires 18 and 17, contact 16 of relay G¹, wire 15, adjustable resistance 14, wire 13, contact 70 12—12^b of release W, and wires 198 and 159 back

to battery Q³. Relay L now closes its front and reverse contacts, causing relay P to be energized by current flowing from battery Q¹, through wires 54 and 55, contact 200 of relay L, wire 201, contact 202 of relay L, wires 203 and 204, winding of relay P, and wires 99, 70 and 45 back to battery Q¹. 5 The despatcher now returns release W to its latched position, causing relay L to become de-energized. Relay P, however, continues energized by its stick circuit through contact 101 of 10 relay N. The circuit of relays L, H and I now becomes energized in the normal direction by current of sufficient magnitude to operate relays H and I but not relay L, such current being supplied by battery Q⁴, through a branch path around 15 battery Q⁵ and contact 5 of lever V in the circuit previously traced for relays L, H and I, this branch path passing from battery Q⁴, through wires 114 and 205, contact 206 of lever V, and wire 207 to wire 7. A pick-up circuit for relay R 20 is now closed through battery Q², wire 208, contact 112^a—112 of relay H, contact 40^b—40 of relay L, wire 39, contact 38^a—38 of relay G², wire 37, contact 36^a—36 of relay P, wire 35, contact 34^a—34 of relay N, wire 33, winding of relay R, 25 and wires 32 and 31 back to battery Q². Relay R thereupon closes its normal contacts 126—126^a and 130—130^a, completing the normal operating circuit for motor M, from batteries Q¹ and Q² in series, through contact 124 of relay R, contact 126^a—126 of relay R, wire 127, armature 128 of motor M, wire 129, contact 130—130^a of relay R, wire 131, contact 132^b—132 of circuit controller a, wire 133, field winding 134 of motor M, and wires 135, 67, 68, 70 and 45 back to battery Q¹. 30

If the despatcher permits lever V to remain in the *n* position, signals S¹ and S³ will clear and will operate as non-stick, when the train moves through section B—C—C¹—E, in a manner similar to that described when signals S² and S⁴ 40 are cleared by lever V in its *r* position. The operating mechanism of signal S¹ is supplied with current from battery Q¹, through wires 54, 78, 79 and 184, contact 165 of relay G², wire 166, contact 167—167^a of relay R, wire 210, contact 211 of relay H, wire 212, contact 213 of relay L, wire 214, contact 215 of circuit controller a, wire 216, contact 217 of relay g¹, wire 218, operating mechanism of signal S¹, and wires 176, 51 and 52 back to battery Q¹. The operating mechanism of signal S³ is supplied with current by the circuit just traced for signal S¹, as far as contact 215 of circuit controller a, thence through wire 219, contact 220 of relay g¹, wire 221, operating mechanism of signal S³, and wires 222, 180, 181, 44 and 45 back to battery Q¹. Relay N becomes de-energized by the opening of contacts 62 and 60, operated by signals S¹ and S³, respectively. Relay P, however, continues closed by its pick-up circuit previously traced through contact 95 of circuit controller a and contact 97 of relay J. Hence, until an approaching train de-energizes relay J, by first de-energizing either relay G¹ or G³, the despatcher can change the position of switch F without operating release W. When an approaching train de-energizes relay J, and thereby de-energizes also relay P, the despatcher must operate release W if he then wishes to change the position of switch F before a train enters section B—C—C¹—E. 65

As a train enters section A—B, de-energizing relay G¹, relay J becomes de-energized due to the opening of its pick-up circuit through contact 72 of relay G¹ and its stick circuit through contact 87 of relay G¹. Due to the momentary 70 75

de-energization of relay I when the train enters section A—B, contact 141—141^b of relay I closes, for a brief period, the lighting circuit for lamp e previously traced through this contact, except that the circuit now passes through a branch path around contact 138 of lever V, which branch path passes from wire 136, through wire 160, and contact 234 of lever V to wire 140. Relay G², upon becoming de-energized by such a train entering section B—C—C¹—E, closes its back contact 191, thereby completing a pick-up circuit for relay J, from battery Q¹, through wires 54, 78, 79, 81, 94 and 186, contact 187—187^a of circuit controller a, wire 223, contact 224—224^a of relay g³, wires 225 and 188, contact 189^b—189 of relay g¹, wire 190, contact 191 of relay g², wires 192 and 76, winding of relay J, and wires 77, 68, 70 and 45 back to battery Q¹. When relay G² becomes energized after the train leaves section B—C—C¹—E, relay J continues energized by a stick circuit which is closed through battery Q¹, wires 54, 78, 79 and 81, contact 82—82^a of circuit controller a, wire 83, contact 226 of relay g³, wires 227 and 86, contact 87 of relay G¹, wires 88 and 89, contact 90 of relay G², wire 91, contact 92 of relay J, wire 93, winding of relay J, and wires 77, 68, 70 and 45 back to battery Q¹. Relay H, having been de-energized when the train de-energized relay G², now again becomes energized, without further action by the despatcher, when relay G² becomes energized. With relays H and G² energized, the operating circuit of signal S³ is closed, causing the arm of that signal to move to the "proceed" position. Since relay J continues energized, by a stick circuit, while the train is moving through section C—D, and while signal S³ is clear, the despatcher can reverse switch F, as soon as relay G² has become energized, without having to operate time release W. When the train has moved out of section C—D, relay G³, becoming energized, closes the operating circuit of signal S¹, causing that signal to again display the "proceed" indication. It is clear, then, that with lever V in its n position, non-stick operation is provided for signals S¹ and S³. With lever V in its p position, stick operation of signals S¹ and S³ is provided similarly to that of signals S² and S⁴ when lever V is in its t position.

When a westbound train enters section C—D, relay G³ opens the pick-up circuit of relay g³ and then, by means of contact 53—53^b, closes a shunt circuit for relay g³ similar to that closed for relay g¹ by contact 48—48^b of relay G¹. Relay g³ is then slow in opening its front contacts and in closing its back contacts, and causes the circuit of relays H and I to be open for the interval between the opening of contact 22 of relay G³ and the closing of a branch path, around this contact, through contact 184 of relay g³. Relay G³, upon becoming de-energized, opens, at contacts 74 and 85, the pick-up and stick circuits, respectively, of relay J. When the train de-energizes relay G², relay J becomes energized by a pick-up circuit which differs from the circuit previously traced through contact 187—187^a of circuit controller a only in that it includes a branch path which passes from wire 223, through contact 224—224^b of relay g³, wire 274, and contact 189^a—189 of relay g¹ to wire 190. As the train moves through section A—B, after leaving section B—C—C¹—E, relay J is energized by a stick circuit which differs from the stick circuit previously traced through contact 82—82^a of circuit controller a, and contact 85 of relay G³.

only in that it includes a branch path which passes through contact 228 of relay g¹.

If, upon the completion of an operation of switch F to its reverse position, the despatcher returns lever V to its d position before signals S² and S⁴ clear, relay P continues energized by its stick circuit through contact 101 of relay N, and the despatcher can then at any time return switch F to its normal position, by moving lever V to its n position, without operation of release 101 W. Such operation of switch F to its normal position and the subsequent clearing of signals S¹ and S³, controlled by the movement of lever V from its d to its n position, is similar to the operation of switch F to its reverse position and the subsequent clearing of signals S² and S⁴, controlled by the movement of lever V from its b to its r position as already described.

In Fig. 2, derail F^e is shown in its normal or derailing position and switch F, as in Fig. 1, is shown in its normal position. Primary indication relay f is now energized by current flowing from battery Q², through wires 237 and 238, contact 239—239^a of circuit controller a^e, contact 241^a—241 of circuit controller a, wire 242, winding of relay f, and wire 243 back to battery Q². Secondary indication relay K is energized by current flowing from battery Q², through wires 237 and 245, contact 246 of relay f, wire 247, winding of relay K, and wires 248 and 243 back to battery Q². If the despatcher now wishes to reverse switch F and derail F^e to permit traffic movements to or from siding Y, he will move lever V to its r position, and current will flow through relays L, H and I, as previously described in connection with Fig. 1. Relay L, upon becoming energized, causes relay R to become energized in its reverse direction. Relay R, upon closing its contact 107^b—107 completes the reverse pick-up circuit for relay R^e, including battery Q¹, wire 236, winding of relay R^e, wire 235, contact 107—107^b of relay R, and wires 148, 70 and 45 back to battery Q¹. Relay R, upon closing its reverse contacts, completes the operating circuit previously traced in connection with Fig. 1 for motor M, which then moves switch F to its reverse position. Relay R^e, upon becoming energized by the reverse pick-up circuit traced through contact 107^b—107 of relay R, causes the operation of motor M^e in like manner as relay R causes the operation of motor M.

As soon as circuit controller a opens its contact 241—241^b while switch F is being unlocked, the circuit previously traced for relay f is broken, and relay f, then becoming de-energized, opens its contact 246, in turn causing relay K to become de-energized. When switch F and derail F^e have become locked in their reverse positions, current flows in a portion of the circuit previously traced for relay f as far as wire 238, thence through contact 239—239^b of circuit controller a^e, contact 241^b—241 of circuit controller a, wire 242, winding of relay f, and wire 243 back to battery Q². Contact 250 of relay f and contact 252 of relay K are connected in series and are substituted, in the circuit for relays L, H and I, in place of contact 19 of circuit controller a shown in Fig. 1. Indication relay I therefore becomes de-energized for a period lasting from the opening of contact 250—250^a, until the closing of contact 252—252^b in series with contact 250—250^b, thus causing lamp e to become lighted for a corresponding period and again for a similar period from the time of opening of contact 250—250^b, until the closing of contact 252—252^a.

in series with contact 250—250^a when switch F and derail F^e have completed their operation to the reverse position. Contact 256 of circuit controller a^e, closed only while derail F^e is locked in its reverse position, is inserted in the operating circuit of signals S² and S⁴ between contact 171 of relay L and contact 173 of circuit controller a, thus ensuring that derail F^e, as well as switch F, has been moved to its reverse position before signals S² and S⁴ will clear. The operation when switch F and derail F^e are returned from the reverse to the normal position is similar to that just described and will be readily understood without further description.

15 In Fig. 3, each part is shown in the same position and state of energization as the similar part of Fig. 2, except that relays f and K are de-energized, whereas, in Fig. 2 they are energized. If, with the arrangement of Fig. 3, the despatcher 20 moves lever V to its r position to cause the operation of switch F and derail F^e to their reverse positions, contact 261 of switch F will first become closed as soon as the locking mechanism of switch F starts to unlock switch F, and primary indication relay f will then be energized by current flowing from battery Q², through wires 258 and 259, contact 261 of circuit controller a, wires 262 and 263, winding of relay f, and wire 264 back to battery Q². The pick-up 25 circuit for relay K will then become closed through battery Q², wires 258 and 269, contact 270 of relay f, wire 271, winding of relay K, and wires 272 and 264 back to battery Q². Relay f, upon becoming energized, opens its contact 250—250^b, 30 and, after an interval of time, relay K closes its contact 252—252^a in series with contact 250—250^a of relay f. When the locking mechanism of derail F^e starts to unlock derail F^e a branch path will be closed around contact 261 in the circuit 35 just traced for relay f, this branch path passing from wire 259, through wire 265, contact 267 of circuit controller a^e, and wire 268 to wire 263. During the interval between the opening of contact 250—250^b and the closing of contact 252—252^a, relay I is de-energized, thus causing lamp e to be lighted for a corresponding period. When switch F and derail F^e become locked in their reverse positions, contacts 261 and 267 40 again open and relay f again becomes de-energized, causing relay K to also become de-energized. Relay I is again de-energized for a period from the opening of contact 250—250^a, until the closing of contact 252—252^b of relay K, causing lamp e to be lighted for a similar period. 45 Relay K is so constructed that a greater time is required for opening its front contacts when its control circuit is broken, than is required for the opening of its back contacts when its control circuit becomes closed. It will therefore be clear 50 that with the arrangement of Fig. 2, lamp e will be lighted for a longer period while switch F and derail F^e are being unlocked than while they are being locked. Whereas, with the arrangement of Fig. 3, the reverse is true, namely, 55 that lamp e will be lighted for a longer period while switch F and derail F^e are being locked than while they are being unlocked.

Although I have herein shown and described only three forms of remote controlling apparatus embodying my invention, it is understood that various changes and modifications may be made therein within the scope of the appended claims without departing from the spirit and scope of my invention.

Having thus described my invention, what I claim is:

1. In combination with a railway traffic governing device, a first control relay, a second control relay responsive only to current of greater magnitude than that required for the operation of said first relay, means for controlling the operation of said device to one position or another according as the front contacts of said second relay are closed or the front contacts of said first relay are closed while the back contacts of the second relay are closed, manually operable means for at times supplying current of one magnitude to the coils of said first relay, and manually operable means for at times supplying current of a greater magnitude to the coils of said second relay.

2. In combination with a railway traffic governing device, a first control relay, a second control relay responsive only to current of greater magnitude than that required for the operation of said first relay, means for controlling the operation of said device to one position or another according as the front contacts of said second relay are closed or the front contacts of said first relay are closed while the back contacts of the second relay are closed, manually operable means for at times supplying current to said first and second relays in series and of sufficient magnitude to operate the first relay but not the second relay, and manually operable means for at times supplying current to said first and second relays in series and of sufficient magnitude to operate the second relay.

3. In combination, a railway traffic governing device, a first control relay, a second control relay responsive only to current of greater magnitude than that required for the operation of said first relay, means for controlling the operation of said device to one position or another according as the front contacts of said second relay are closed or the front contacts of said first relay are closed while the back contacts of the second relay are closed, a locking mechanism for said device operated in conjunction therewith, a device contact arranged to open for a brief period while said locking mechanism is locking said device and for another brief period while said locking mechanism is unlocking said device, a detector track circuit for said device including a track relay, one or more approach track circuits for said device each including a track relay, a repeater relay for each such approach track relay controlled by a front contact thereof, a snubbing circuit for each of said approach track relay repeaters including a back contact of its approach track relay, a pair of contacts for each of said approach track circuits comprising a front contact of the corresponding approach track relay in multiple with a back contact of its repeater relay, a circuit including one of said pairs of contacts for each of said approach track circuits and a front contact of said detector track relay as well as said device contact and said first and second control relays in series, an indication relay also in series with said contacts and said control relays in said circuit and responsive to the open circuit intervals of said device contact and to the open circuit interval between the opening of the approach track relay contact and the closing of the repeater relay contact of each of said pairs of contacts as well as to the opening of said detector track relay contact, indication means controlled by said indication relay, and manually operable means for at times supplying current to said circuit of sufficient magnitude.

cient magnitude to operate said first control relay and said indication relay but not said second control relay and for at times supplying current to said circuit of sufficient magnitude to operate 5 said second control relay as well as said first control relay and said indication relay.

4. In combination, a railway track circuit including a track relay, a signal for governing traffic over said track circuit, a manually operable 10 lever having a normal position and a first and a second control position, means effective when said lever is moved from normal to said second position while said track relay is energized to cause said signal to display a "proceed" indication, 15 means causing said signal to continue to display a "proceed" indication when said lever is moved from said second to said first position while said track relay is energized, means causing said signal to display a "stop" indication when said track 20 relay becomes de-energized, means effective when said track relay becomes energized while said lever is in said second position to cause said signal to display a "proceed" indication without further manipulation of said lever, and means effective 25 when said track relay becomes energized while said lever is in said first position to require the lever to be returned to normal or to said second position in order to cause said signal to display a "proceed" indication.
- 30 5. In combination, a railway track circuit including a track relay, a signal for governing traffic over said track circuit, a control relay, means causing said signal to display its clear indication while said control relay is energized, an 35 indication relay, a signal stick relay, a manually operable lever having a first and a second position, a pick-up circuit for said stick relay controlled by a contact closed while said lever is in said second position, a stick circuit for said stick 40 relay controlled by a contact of said indication relay, a circuit including said control relay and said indication relay as well as a contact of said track relay and a contact of said stick relay in series, and means for supplying current to said 45 circuit through a contact closed while said lever is in said first or said second position or while said lever is in any position intermediate between said first and second positions to energize said control relay and said indication relay.
- 50 6. In combination with a railway traffic governing device, a neutral control relay, a polarized control relay responsive only to current of greater magnitude than that required for the 55 operation of said neutral relay, means for controlling the operation of said device to one position or another according as the front and normal contacts of said polarized relay are closed or the front contacts of said neutral relay are closed while the back contacts of said polarized 60 relay are closed, means for at times supplying current to said neutral and polarized relays in series and of sufficient magnitude to operate the neutral but not the polarized relay, means for at 65 times supplying current to said neutral and polarized relays in series and of sufficient magnitude to operate the polarized relay as well as the neutral relay, one or more approach track circuits for said device and each such approach circuit including a track relay, approach locking means for at 70 times preventing the operation of said device when any one of said approach track relays is de-energized, manually operable means for at times energizing said polarized relay in reverse direction, and means including a front and a re-

verse contact of said polarized relay for at times nullifying said approach locking means.

7. In combination with a railway traffic governing device, control means for said device supplied with current by a manually operable means, 5 an approach track circuit for said device including a track relay, approach locking means for at times preventing the operation of said device when said approach track relay is de-energized, a release relay for at times nullifying said approach locking means, an indication relay, indication means controlled by said indication relay, a circuit including said indication relay and said release relay in series, manually operable means for at times supplying current to said circuit of sufficient magnitude to operate said indication relay but not said release relay, and manually operable means for at times increasing the current supplied to said release relay to a magnitude sufficient to operate said release relay. 10 15 20

8. In combination, a railway switch, manually operable means for controlling the operation of said switch to one position or the other, normal contacts operated in conjunction with said switch and arranged to be closed while said switch is 25 in its normal position only, reverse contacts operated in conjunction with said switch and arranged to be closed while said switch is in its reverse position only, a detector track circuit for said switch including a track relay, a first approach track circuit adjoining one end of said detector circuit and including a track relay, a second approach track circuit adjoining the opposite end of said detector track circuit and including a track relay, a first approach repeater relay controlled by said 30 first approach track relay, a second approach repeater relay controlled by said second approach track relay, a directional approach stick relay, indication means controlled by said stick relay, a first pick-up circuit for said stick relay controlled by a front contact of said first approach track relay and a front contact of said second approach track relay, a second pick-up circuit for said stick relay controlled by one of said normal switch contacts and a front contact of said 35 first approach repeater relay as well as a back contact of said second approach repeater relay and a back contact of said detector track relay, a third pick-up circuit for said stick relay controlled by one of said normal switch contacts and a front contact of said 40 first approach repeater relay as well as a back contact of said second approach repeater relay and a back contact of said detector track relay, a fourth pick-up circuit for said stick relay controlled by one of said reverse switch 45 contacts and a back contact of said second approach repeater relay as well as a back contact of said detector relay, a first stick circuit for said stick relay controlled by one of said normal switch contacts and a front contact of said 50 detector relay as well as a front contact of said second approach repeater relay and a back contact of said detector relay, a fourth pick-up circuit for said stick relay controlled by one of said reverse switch 55 contacts and a back contact of said second approach repeater relay as well as a back contact of said detector relay, a first stick circuit for said stick relay controlled by one of said normal switch contacts and a front contact of said 60 detector relay as well as a front contact of said first approach track relay and a front contact of said second approach track relay, a second stick circuit for said stick relay differing from said first stick circuit only in being controlled by a back contact of said first approach repeater relay instead of by a front contact of said first approach track relay, a third stick circuit for said stick relay differing from said first stick circuit only in being controlled by a back contact of said 65 second approach repeater relay instead of by a front contact of said second approach track relay, a fourth stick circuit for said stick relay controlled by one of said reverse switch contacts and a front contact of said first approach track relay 70 75

- as well as a front contact of said second approach track relay and a front contact of said detector relay, and a fifth stick circuit for said stick relay differing from said fourth stick circuit 5 only in being controlled by a back contact of said second approach repeater relay instead of by a front contact of said second approach track relay.
9. In combination, a railway switch which in its normal position directs traffic over a first track only and in its reverse position directs traffic from said first track to a second track or from said second track to said first track, a neutral control relay, a polarized control relay responsive only to current of greater magnitude 10 than that required for the operation of said neutral relay, manually operable means for at times supplying current of normal polarity to said neutral and polarized relays in series and of sufficient magnitude to operate the neutral but not the polarized relay, manually operable means for at times supplying current of normal polarity to said neutral and polarized relays in series and of sufficient magnitude to operate the neutral but not 15 the polarized relay, manually operable means for at times supplying current of normal polarity to said neutral and polarized relays in series and of sufficient magnitude to operate the polarized relay as well as the neutral relay, manually operable means for at times supplying current of reverse polarity to operate said polarized relay to the reverse position, normal switch contacts closed only while said switch is in its normal position, reverse switch contacts closed only while 20 said switch is in its reverse position, a detector track circuit for said switch including a track relay, a first approach track circuit adjoining one end of said detector circuit in said first track and including a track relay, a second approach track circuit adjoining the other end of said 25 detector circuit in said first track and including a track relay, a first and a second approach repeater relay controlled respectively by said first and said second approach track relays, a directional approach stick relay controlled by said 30 first and said second approach track relays and by said first and said second approach repeater relays as well as by said detector relay and one or more said normal and one or more said reverse switch contacts, a plurality of signals governing traffic over said switch, a signal back locking relay energized only when all of said signals indicate "stop", an approach stick locking relay controlled by said polarized relay in its reverse 35 position and by said detector track relay and 30 said directional approach stick relay as well as by said back locking relay and one of said switch contacts, a stick polarized switch relay, a first and a second source for supplying current to the coils of said switch relay, a first pick-up circuit 40 for said switch relay passing from the positive side of said first source through a front contact of said neutral control relay and a back contact of said polarized control relay as well as a front contact of said stick locking relay and a front 45 contact of said back locking relay and also a front contact of said detector track relay in series and then through the coils of said switch relay to negative side of said first source, a second pick-up circuit for said switch relay passing from the 50 negative side of said second source through a normal and a front contact of said polarized control relay and a front contact of said stick locking relay as well as through a front contact of said back locking relay and a front contact of 55 said detector relay in series and then through the coils of said switch relay to positive side of said second source, a first stick circuit for said switch relay controlled by a back contact of said detector track relay, a second stick circuit for 60 said switch relay controlled by a back contact of said back locking relay, a third stick circuit for said switch relay controlled by a back contact of said stick locking relay, a fourth stick circuit for 65 said switch relay controlled by a back contact of said neutral control relay and a back contact of said polarized control relay, means including a normal contact of said switch relay for at times supplying current from said first source through any one of said stick circuits in normal direction 70 to the coils of said switch relay, means including a reverse contact of said switch relay for at times supplying current from said second source through any one of said stick circuits in reverse direction to the coils of said switch relay, means 75
10. In combination, a railway switch which in its normal position directs traffic over a first track only and in its reverse position directs traffic from said first track to a second track or from said second track to said first track, a neutral control relay, a polarized control relay responsive only to current of greater magnitude than that required for the operation of said neu-

for operating said switch to one position or the other according as said switch relay is energized in the normal or reverse direction, means for controlling through a normal contact of said switch relay and a front contact of said neutral control relay as well as a back contact of said polarized control relay and one of said normal switch contacts those of said signals which govern traffic over said switch in its normal position, and means for controlling through a reverse contact of said switch relay and one of said reverse switch contacts as well as a front and a normal contact of said polarized control relay those of said signals which govern traffic over said switch in its reverse position.

11. In combination, a railway switch, a neutral control relay, a polarized control relay responsive only to current of greater magnitude than that required for the operation of said neutral relay, means for controlling the operation of said switch to one position or the other according as the front and normal contacts of said polarized relay are closed or the front contacts of said neutral relay are closed while the back contacts of said polarized relay are closed, a plurality of normal switch contacts each closed while said switch is in its normal position, a plurality of reverse switch contacts each closed while said switch is in its reverse position, a detector track circuit for said switch including a track relay, one or more approach track circuits for said switch and each such approach circuit including a track relay, a directional approach stick relay, means controlled according to the position of said switch for causing said approach stick relay to be de-energized while one of said approach track relays is de-energized by an approaching train and causing said approach stick relay to become energized while said detector track relay is de-energized by said train and causing said approach stick relay to continue energized while said train is receding from said switch, a plurality of signals governing traffic over said switch, an approach stick locking relay, means controlled according to the position of said switch for causing said stick locking relay to become de-energized by certain of said signals being operated away from their stop position or by certain others of said signals continuing or being operated away from their stop position while said approach stick relay is de-energized, means for at times controlling said stick locking relay by a reverse contact of said polarized relay, means for selectively controlling said signals by said neutral control relay and by said polarized control relay in its energized normal position according as said switch is in its normal or reverse position, an indication relay, a clockwork release latched normal, a first asymmetric unit through which current can flow in one direction only, a circuit including said neutral and polarized control relays and said indication relay as well as said first asymmetric unit and a front contact of said detector relay and also a normally closed contact of said clockwork release in series, a manually operable lever having a first and a second position as well as a third and a fourth and also a fifth and a sixth position, means including said lever while in said first or second positions or at any point between these two positions for supplying current in a normal direction to said circuit and of sufficient magnitude to operate said indication and neutral control relays but not said polarized control

relay, means including said lever while in said fifth or sixth positions or at any point between these two positions for supplying current in a normal direction to said circuit and of sufficient magnitude to operate said polarized control relay as well as said neutral control relay and said indication relay, a branch path around that portion of said circuit which includes said neutral control relay and said detector relay contact as well as said first asymmetric unit and said branch path including a back contact of said approach stick relay in multiple with a back contact of said approach stick locking relay and both said approach stick relay contact and said approach stick locking relay contact in series with a second asymmetric unit through which current can flow in reverse direction only to that required for energizing said polarized control relay in its normal direction, means including said lever while in said third or fourth positions or at any point between these two positions for supplying current in reverse direction to the circuit through said branch path and of sufficient magnitude to operate said indication relay but not said polarized control relay, means including a normally closed and a normally open contact of said clockwork release for at times respectively removing said indication relay from said circuit and supplying current in reverse direction to the remaining portion of said circuit through said branch path and of sufficient magnitude to energize said polarized control relay in the reverse direction, and indication means controlled by said lever and said clockwork release as well as by said indication relay.

12. In combination with a railway traffic governing device, a polarized relay, a control circuit including said polarized relay, means for supplying current of one polarity or the other to said control circuit, a signal for governing traffic over said device, means for opening said control circuit whenever said signal indicates other than "stop", means effective after said control circuit is opened and including a normal or a reverse contact of said polarized relay for supplying current to said polarized relay in the same direction as current was last supplied thereto before said control circuit was opened, means for operating said device to one position or another according as said polarized relay is energized in one direction or the other, and means for controlling said signal.

13. In combination with a railway traffic governing device, a control means for said device, manually operable means for at times supplying current to operate said control means, an approach track circuit for said device including a track relay, means controlled by said approach track relay for causing an indication to be displayed for a brief period when a train approaching said device de-energizes said approach track relay while said manually operable means is in the position for supplying current to operate said control means, and means controlled by said approach track relay for causing an indication to be displayed for a longer period when a train approaching said device de-energizes said approach track relay while said manually operable means is not in the position for supplying current to operate said control means.

14. In combination, a railway traffic governing device and a locking mechanism for said device operated in conjunction therewith, a first control relay, a second control relay responsive only

to current of greater magnitude than that required for the operation of said first control relay, means for controlling the operation of said device to one position or another according as the front contacts of said second control relay are closed or the front contacts of said first control relay are closed while the back contacts of the second control relay are closed, a device contact arranged to open for a brief period while 10 said locking mechanism is locking said device and for another brief period while said locking mechanism is unlocking said device, an indication relay responsive to the open periods of said device contact, manually operable means for at 15 times supplying current of different magnitudes over a pair of conductors to said first and second control relays as well as said device contact and said indication relay in series, an approach track circuit for said device including a track 20 relay, means controlled by said approach track relay for opening the circuit through one of said conductors for a period which although brief is of sufficient duration to cause said indication relay to respond when said approach relay becomes 25 deenergized, and indication means controlled by said indication relay.

15. In combination, a railway traffic governing device and a locking mechanism for said device operated in conjunction therewith, a first control relay, a second control relay responsive only to current of greater magnitude than that required for the operation of said first control relay, means for controlling the operation of said device to one position or another according as 30 the front contacts of said second control relay are closed or the front contacts of said first control relay are closed while the back contacts of the second control relay are closed, an indication relay, a first conductor extending from a remote 35 point to a point adjacent said device, a second conductor of similar extent as said first conductor, a circuit including said first and second control relays as well as said first and second conductors in series, a signal for governing the 40 movement of traffic over said device, an approach track circuit for said signal including a track relay, a detector track circuit for said device including a track relay, a manually operable lever for at times supplying current to said 45 circuit of sufficient magnitude to operate said first control relay but not said second control relay and for at times supplying current to said circuit of sufficient magnitude to operate said second as well as said first control relay, means 50 for controlling said signal according to the energization of said first and second control relays, means controlled by said lever and said indication relay for so controlling said first and second control relays as to provide non-stick control for said 55 signal while said lever is in one position and stick control for said signal while said lever is in another position, and means for so controlling said indication relay over said first and second conductors as to cause a momentary indication to be 60 displayed while said locking mechanism is unlocking said device and again while said locking mechanism is locking said device and another momentary indication when said approach relay becomes de-energized while said lever is in a position for clearing said signal as well as a continuous indication while said detector relay is de-energized or while said approach relay is de-energized while said lever is in a position for keeping said signal at stop, and means for so 65 supplying current to said circuit that one of said conductors can be used as a common conductor for providing controls and indications in connection with one or more additional devices.

65. In combination, a plurality of railway traffic governing devices, a locking mechanism for each of said devices operated in conjunction therewith, a normal and a reverse contact for each of 70 said devices so arranged that said normal contact will be closed only while the respective device is locked in its normal position and said reverse contact will be closed only while said respective device is locked in its reverse position, a first indication relay, a first control circuit for said first indication relay controlled by said normal contact of each of said devices, a second control circuit for said first indication relay controlled by said reverse contact of each of said devices, 75

device and a locking mechanism for said device operated in conjunction therewith, a neutral control relay, a polarized control relay responsive only to current of greater magnitude than that required for the operation of said neutral control relay, means for controlling the operation of said device to one position or another according as a front and a neutral contact of said polarized control relay are closed or a front contact of said neutral control relay is closed while a back contact of said polarized control relay is closed, an indication relay, a first conductor extending from a remote point to a point adjacent said device, a second conductor of similar extent as said first conductor, a circuit including said neutral and polarized control relays as well as said first and second conductors in series, a signal for governing the movement of traffic over said device, an approach track circuit for said signal including a track relay, a detector track circuit for said device including a track relay, a manually operable lever for at times supplying current of normal polarity to said circuit of sufficient magnitude to operate said neutral control relay but not said polarized control relay and for at times 25 supplying current of normal polarity to said circuit of sufficient magnitude to operate said polarized control relay in its normal direction, auxiliary manually operable means for at times supplying current of reverse polarity to said circuit 30 of sufficient magnitude to operate said polarized control relay in its reverse direction, means for controlling said signal according to the energization of said neutral and polarized control relays, means controlled by said lever and said indication 35 relay for so controlling said neutral and polarized control relays as to provide non-stick control for said signal while said lever is in one position and stick control for said signal while said lever is in another position, approach locking means 40 for at times preventing the operation of said device while said approach relay is de-energized, means including a front and a reverse contact of said polarized control relay for releasing said approach locking means, means for so controlling 45 said indication relay over said first and second conductors as to cause a momentary indication to be displayed while said locking mechanism is unlocking said device and again while said locking mechanism is locking said device and another 50 momentary indication when said approach relay becomes de-energized while said lever is in a position for clearing said signal as well as a continuous indication while said detector relay is de-energized or while said approach relay is de-energized while said lever is in a position for keeping said signal at stop, and means for so 55 supplying current to said circuit that one of said conductors can be used as a common conductor for providing controls and indications in connection with one or more additional devices.

70. In combination, a plurality of railway traffic governing devices, a locking mechanism for each of said devices operated in conjunction therewith, a normal and a reverse contact for each of 75 said devices so arranged that said normal contact will be closed only while the respective device is locked in its normal position and said reverse contact will be closed only while said respective device is locked in its reverse position, a first indication relay, a first control circuit for said first indication relay controlled by said normal contact of each of said devices, a second control circuit for said first indication relay controlled by said reverse contact of each of said devices, 75

- 5 a second indication relay controlled by a front contact of said first indication relay, control means for said devices, a first conductor extending from a remote first point to a second point
- 10 5 adjacent said devices, a second conductor also extending from said first to said second point, a circuit including said control means and a front contact of said first and of said second indication relay as well as said first and second conductors in series, a branch path including a back contact of said first and of said second indication relay in series and said branch path being in multiple with that portion of said circuit which includes said front contacts of said first and second indication relays, manually operable means for supplying current to said circuit, and indication means responsive to the open periods of said circuit caused by said front and said back contacts of said first and second indication relays.
- 15 20 18. In combination, a plurality of railway traffic governing devices and a contact operated in conjunction with each of said devices, a first indication relay controlled by each of said contacts, a slow release second indication relay controlled by a front contact of said first indication relay, control means for said devices supplied with current by a pair of conductors from a remote point, and indication control means also supplied with current by said pair of conductors and so controlled by said first and second indication relays as to cause an indication to be displayed for a certain period of time when any of said locking mechanisms starts unlocking the corresponding device after all the said devices have been locked 30 35 and to cause an indication to be displayed for a longer or a shorter period of time when any of said locking mechanisms completes locking its device while all the other said devices are completely locked.
- 40 45 19. In combination, a relay for controlling a railway traffic governing device, a second relay for controlling said device, a circuit including said two relays in series, means for controlling said first relay, means for controlling said second relay, means controlled by a front contact of said first relay for putting said device into a given condition, and means controlled by a front contact of said second relay for putting said device into a second condition.
- 50 55 20. In combination, a relay, a second relay, means for selectively controlling said two relays in series by current of a given polarity, a railway track switch, means controlled by said first relay for operating said switch to a given position, and means controlled by said second relay for operating said switch to a second position.
- 60 65 21. In combination, a relay, a second relay, means for selectively controlling said two relays in series, a railway track switch, means controlled by said first relay for operating said switch to a given position, and means controlled by said second relay for operating said switch to a second position.
- 70 75 22. In combination, a relay, a second relay, a circuit including said two relays, means for selectively controlling said two relays, a railway track switch, means controlled by said first relay for operating said switch to a given position, and means controlled by said second relay for operating said switch to a second position.
23. In combination, a railway track switch, a polarized relay, means for controlling said relay in normal and reverse directions, means controlled by a normal polar contact of said relay for controlling said switch, locking means for preventing operation of said switch, and means controlled by a reverse polar contact of said relay for releasing said locking means.
24. In combination, a neutral relay, a polarized relay, means for controlling said two relays, a railway track switch, means controlled by said neutral relay for controlling said switch, means controlled by a normal polar contact of said polarized relay for controlling said switch, locking means for preventing operation of said switch, and means controlled by a reverse polar contact of said relay for releasing said locking means.
25. In combination, a railway traffic governing device, a second railway traffic governing device, a polarized relay, means for controlling said relay in normal and reverse directions, means controlled by a normal contact of said relay for controlling said first device, locking means for preventing operation of said second device, and means controlled by a reverse contact of said relay for releasing said locking means.
26. In combination, a railway signal, a track switch over which traffic movements are governed by said signal, a polarized relay, means for controlling said relay in normal and reverse directions, means controlled by a normal contact of said relay for controlling said signal, locking means for preventing operation of said switch, and means controlled by a reverse contact of said relay for releasing said locking means.
27. In combination, a railway traffic governing device, a second railway traffic governing device, a polarized relay, means for energizing said relay in the normal direction, means controlled by a normal polar contact of said relay for controlling said first device, a manually controllable time element device, means controlled by said time element device for energizing said relay in the reverse direction upon the lapse of a measured interval of time after said relay has been energized in the normal direction, and means controlled by a reverse polar contact of said relay for controlling said second device.
28. In combination, a railway track switch, a polarized relay, means for energizing said relay by current of normal polarity, means controlled by a normal polar contact of said relay for controlling said switch, a manually controllable time element device, means controlled by said time element device for energizing said relay in the reverse direction upon the lapse of a measured interval of time after said relay has been energized in the normal direction, and means controlled by a reverse polar contact of said relay for controlling said switch.
29. In combination, an indication relay which becomes energized or deenergized as controlled by a railway traffic governing device, an indication means, means controlled by said relay for energizing said indication means for a given period when said relay becomes energized, and means controlled by said relay for energizing said indication means for a different period when said relay becomes deenergized.
30. In combination, an indication relay controlled by a railway track switch, a slow-release relay controlled by said indication relay, an indication means, and means controlled by said indication relay and by said slow-release relay for controlling said indication means.
31. In combination, a railway track circuit including a track relay, a signal for governing traffic movements over said track circuit, a manually operable lever having a normal position and a first and a second control position, a con-

tact controlled by said lever and closed when said lever is in its first position, a second contact controlled by said lever and closed when said lever is in its second position, means controlled by said first lever contact and by a contact of said track relay for causing said signal to display a proceed indication while said lever is in its first position, a stick relay controlled by said second lever contact and by a contact of said track relay, and means controlled by said stick relay for causing said signal to continue to display a proceed indication when said lever is moved from its first to its second position.

32. In combination, a railway track circuit including a track relay, a signal for governing traffic movements over said track circuit, a manually operable lever having a normal position and a first and a second position, a first and a second contact controlled by said lever, each of which is closed when said lever is in its first position, a third contact controlled by said lever and closed when said lever is in its second position, a stick relay, a pick-up circuit for said relay controlled by said first lever contact, a stick circuit for said relay controlled by a contact of said track relay, a non-stick control circuit for said signal controlled by a contact of said track relay and by said second lever contact, and a stick second control circuit for said signal controlled by said third lever contact and by a contact of said stick relay.

33. In combination with a section of railway track, a switch in said section, a track relay for said section, a signal governing traffic over said switch, a control circuit for controlling said signal from a distant point, a manually controlled device, a stick relay at said distant point controlled by said device and by said signal control circuit, a second stick relay adjacent said switch controlled by said first stick relay and by said track relay, and means controlled by said second stick relay for controlling said switch.

34. In combination, a railway track switch, a polarized switch relay for controlling said switch, a track circuit for said switch including a track relay, a normal and a reverse pick-up circuit for energizing said switch relay, and a stick circuit for said switch relay including one of its own polar contacts and a back contact of said track relay for retaining said switch relay in an energized condition as long as said track relay remains deenergized.

35. In combination, a railway track switch, a polarized switch relay for controlling said switch, a track circuit for said switch including a track relay, a normal and a reverse pick-up circuit controlled by a front contact of said track relay for energizing said switch relay, and a stick circuit for said switch relay including one of its own polar contacts and controlled by a back contact of said track relay for retaining said switch relay in an energized condition as long as said track relay remains deenergized.

36. In combination with a railway track switch, a polarized switch relay for controlling said switch, a manually controllable pole-changer, a track circuit for said switch including a track relay, a pick-up circuit for said switch relay including a front contact of said track relay, means including said pole-changer for supplying said pick-up circuit with current of normal or reverse polarity, and a stick circuit for said switch relay including one of its own polar contacts and a back contact of said track relay for retaining said switch relay in an energized condi-

tion as long as said track relay remains deenergized.

37. In combination with a railway track switch, a polarized switch relay for controlling said switch, a manually controllable pole-changer, a signal for governing the movement of traffic over said switch, a pick-up circuit for said switch relay which is closed when and only when said signal is controlled for indicating "stop", means including said pole-changer for supplying said pick-up circuit with current of normal or reverse polarity, and a stick circuit for said switch relay including one of its own polar contacts and closed when said signal is controlled for indicating "proceed".

38. In combination, a stretch of railway track, a signal for governing traffic movements in a given direction over said stretch, a second signal for governing traffic movements in a second direction over said stretch, a control relay for said first signal, a time releasing device, a time releasing contact controlled by said device and which at times becomes closed upon the lapse of a measured period of time after the beginning of an operation of said device, a stick relay, a pick-up circuit for said stick relay including a contact operated by said control relay and a contact controlled by said first signal as well as by said time releasing contact, a stick circuit for said stick relay including a contact operated by said control relay and a contact controlled by said first signal, and a signal control circuit including a contact of said stick relay for controlling said second signal.

39. In a system for safely controlling a distant switch machine and receiving distinctive indications of train progress and switch machine operation; the combination with a distant switch machine for operating a track switch, an approach locking relay at said switch machine, a control relay at said switch machine for controlling said switch machine only if said approach locking relay is energized, a lever at a local office for controlling said relay, a line circuit connecting said relay and lever, signal means at said office for indicating opening of said circuit at the relay end of said line circuit, a detector track circuit associated with said track switch, and means at the relay end of said line circuit for opening said line circuit continuously so long as said detector track circuit is occupied.

40. In combination, a stretch of railway track, a control relay, a second control relay, a polarized relay, normal and reverse control circuits for said polarized relay one of which is controlled by a front contact of said first relay but not by a front contact of said second relay and the other of which is controlled by a front contact of said second relay but not by a front contact of said first relay, two signals controlled by said polarized relay for controlling traffic movements over said stretch, and means for clearing one signal or the other according as said polarized relay is energized by its normal or its reverse control circuit.

41. In combination, a railway track switch, a relay having a front and a back contact, a second relay having a front and a back contact, a polarized relay, a normal control circuit for said polarized relay including the front contact of said first relay, a reverse control circuit for said polarized relay including the front contact of said second relay, a stick circuit for said polarized relay including the back contacts of said first and second relays, and means controlled by

said polarized relay for operating said switch to its normal or its reverse position according to the direction of energization of said polarized relay.

42. In combination, two railway signals governing the movement of traffic over conflicting routes, a control relay, a second control relay, a polarized relay, normal and reverse control circuits for said polarized relay controlled by said first and second control relays respectively, stick circuits for said polarized relay controlled by both said first and second control relays, and means controlled by said polarized relay for clearing one signal or the other according as said polarized relay is energized in the normal or the reverse direction.

43. In combination, a stretch of railway track, a control relay, a second control relay, a polarized relay, normal and reverse control circuits for said polarized relay controlled by said first and second control relays respectively, normal and reverse-stick circuits for said polarized relay controlled by normal and reverse contacts respectively of said polarized relay as well as by both of said control relays, two conflicting signals for controlling traffic movements over said stretch, and means for clearing one signal or the other according as said polarized relay is energized in the normal or the reverse direction.

44. In combination, a stretch of railway track, a control relay, a second control relay, a polarized relay, normal and reverse control circuits for said polarized relay one of which includes a front contact of said first relay and the other of which includes a back contact of said first relay and a front contact of said second relay, a stick circuit for said polarized relay including a back contact of said first relay and a back contact of said second relay, two conflicting signals for controlling traffic movements over said stretch, and means for clearing one signal or the other according as said polarized relay is energized in the normal or the reverse direction.

45. In combination, a section of railway track containing a switch, an approach section adjoining said switch section, a second approach section adjoining said switch section, an approach locking relay, a circuit controlled by traffic conditions in said first approach section for controlling said relay, a second circuit controlled jointly by traffic conditions in said switch section and in said second approach section for controlling said relay, and means controlled by said approach locking relay for controlling said switch.

46. In combination, a section of railway track containing a switch, an approach section adjoining said switch section, a second approach section adjoining said switch section, an approach locking relay, a switch section relay controlled by traffic conditions in said switch section, an approach relay controlled by traffic conditions in said first approach section, a second approach relay controlled by traffic conditions in said second approach section, a circuit including a front contact of said first approach relay for controlling said approach locking relay, a second circuit including a back contact of said switch section relay in series with a back contact of said second approach relay for controlling said approach locking relay, and means controlled by said approach locking relay for controlling said switch.

47. In combination, a section of railway track containing a switch, an approach section adjoining said switch section, a signal for governing traffic movements through said switch section into said approach section, an approach locking

relay, a pick-up circuit for said relay controlled by traffic conditions in said switch section and said approach section, a stick circuit for said relay controlled by said signal, and means controlled by said approach locking relay for controlling said switch.

48. In combination, a stretch of railway track including a first and a second section as well as a track switch, approach locking means for at times preventing operation of said switch when a train approaches said switch, and means controlled jointly by traffic conditions in said first section and by traffic conditions in said second section for releasing said switch.

49. In combination, a stretch of railway track including a first and a second section as well as a track switch, locking means controlled by traffic conditions in said stretch for at times preventing operation of said switch, and means controlled jointly by traffic conditions in said first section and by traffic conditions in said second section for releasing said switch.

50. In combination, a section of railway track including a switch, a second section adjacent said switch section, locking means for at times preventing operation of said switch, and means for releasing said locking means if said switch section and said second section are both occupied by a train.

51. In combination, a section of railway track including a switch, a second section adjacent said switch section, locking means for at times preventing operation of said switch, and means for releasing said locking means if said second section is occupied by a train.

52. In combination, a railway track switch, a polarized switch relay for controlling said switch, a track circuit for said switch including a track relay, a normal and a reverse pick-up circuit for energizing said switch relay, and a stick circuit for said switch relay including one of its own polar contacts and a back contact controlled by said track relay for retaining said switch relay in an energized condition as long as said track relay remains deenergized.

53. In combination, a railway track switch, a polarized switch relay for controlling said switch, a track circuit for said switch including a track relay, a normal and a reverse pick-up circuit controlled by a front contact controlled by said track relay for energizing said switch relay, and a stick circuit for said switch relay including one of its own polar contacts and controlled by a back contact controlled by said track relay for retaining said switch relay in an energized condition as long as said track relay remains deenergized.

54. In combination with a railway track switch, a polarized switch relay for controlling said switch, a manually controllable pole-changer, a track circuit for said switch including a track relay, a pick-up circuit for said switch relay including a front contact controlled by said track relay, means including said pole-changer for supplying said pick-up circuit with current of normal or reverse polarity, and a stick circuit for said switch relay including one of its own polar contacts and a back contact controlled by said track relay for retaining said switch relay in an energized condition as long as said track relay remains deenergized.

55. In a system of approach locking for power-operated switches, a stick relay acting when de-energized to prevent operation of said switch, an approach relay de-energized by a train ap-

proaching the switch, and means for energizing said stick relay after a time interval only if said signals indicate stop and said approach relay is energized.

56. In a railroad traffic controlling system, a track switch, a switch machine for operating said track switch, a two-position circuit controller for governing said switch machine, a remotely controlled relay, operating circuits for said two-position circuit controller governed by said remotely controlled relay, holding circuits for said two-position circuit controller governed by said remotely controlled relay, a detector track section, means opening the operating circuits of said two-position circuit controller when said detector track section is occupied, and means preventing operation of said remotely controlled relay when said detector track section is occupied.

57. In a railroad traffic controlling system, a track switch, a switch machine for operating said track switch, a two-position circuit controller for governing said switch machine, a remotely controlled relay, operating circuits for said two-position circuit controller governed by said remotely controlled relay, holding circuits for said two-position circuit controller governed by said remotely controlled relay, a detector track section, means opening the operating circuits of said two-position circuit controller when said detector track section is occupied, and means preventing the opening of said holding circuits for said two-position circuit controller when said detector track section is occupied.

58. In an approach locking system; a track switch; a lock relay which if deenergized prevents operation of said switch; a signal governing traffic over said switch; a detector track relay associated with said switch; an approach relay; and an energizing circuit for said lock relay including a contact closed when said signal is at stop, a back contact of said detector track relay and a front contact of said approach relay.

59. In combination, a railway switch, an approach track section remote from the switch, a detector track section adjacent to the switch, an approach control relay, a normally closed stick circuit to normally energize said relay, a track relay for said approach track section to rupture said stick circuit in response to a train traversing said approach track section, a track relay for the detector track section, a pick-up circuit for said approach control relay controlled jointly by the track relays of the two mentioned track sections, effective to energize said approach control relay only when the track relay of the approach track section is energized and the track relay of the detector track section is deenergized, and means to control the operation of the switch rendered ineffective as long as the approach control relay remains deenergized.

60. In combination, a railway switch, an approach track section remote from the switch, a detector track section adjacent to the switch, an approach control relay, a normally closed stick circuit to normally energize said relay, a track circuit including a track relay for said approach track section to rupture said stick circuit in response to a train traversing said approach track section, a track circuit including a track relay for the detector track section, a pick-up circuit for said approach control relay controlled jointly by the track relays of the two mentioned track circuits effective to energize said approach control relay only when the track relay of the approach track circuit is energized and the track

relay of the detector track circuit is deenergized, and means to control the operation of the switch rendered ineffective as long as the approach control relay remains deenergized.

61. In combination, a railway switch, a traffic governing relay adapted to permit traffic over the switch when moved to one position and to stop traffic when moved to a second position, a normally energized approach control stick relay, a track circuit to deenergize said stick relay in response to a train approaching said switch, a pick-up circuit, means for reenergizing said stick relay effective only after the train has advanced beyond the track circuit and the traffic governing relay is moved to its second mentioned position, and means to control the operation of the switch rendered effective when the approach control stick relay is energized.

62. In combination, a railway switch having a normal and a reverse position, a switch controlling relay having a normal and a reverse position to select the respective positions of the switch, despatcher controlled means to select the respective positions of the switch controlling relay, a detector track circuit adjacent the switch, an approach track circuit remote from the switch, a track relay for each of said track circuits, a normally energized approach stick relay controlled by the track relay of the approach track circuit, and circuit means controlled jointly by the stick relay and the track relay of the detector track circuit arranged to prevent, under certain traffic conditions, the despatcher controlled means from changing the position of the switch controlling relay once a train has entered the approach track circuit until said train advances through said approach track circuit and said detector track circuit.

63. In combination, a railway track switch, a signal for governing traffic movements in a given direction over said switch, a control relay, a circuit including a front contact of said relay for controlling said signal, a switch relay, a stick circuit for said switch relay including a back contact of said control relay, an approach stick relay, a stick circuit for said approach stick relay controlled by a train approaching said signal in said given direction, a pick-up circuit for said approach stick relay including a back contact of said control relay, a pick-up circuit for said switch relay controlled by said approach stick relay, and means controlled by said switch relay for controlling said switch.

64. In a railroad traffic controlling system, a track switch, a switch machine for operating said track switch, a two-position circuit controller for governing said switch machine, a remotely controlled relay, operating circuits for said two-position circuit controller governed by said remotely controlled relay, holding circuits for said two-position circuit controller governed by said remotely controlled relay, a detector track section, means opening the operating circuits of said two-position circuit controller when said detector track section is occupied, and means preventing a particular operation of said remotely controlled relay when said detector track section is occupied.

65. In a railroad traffic controlling system, a track switch, a switch machine for operating said track switch, a two-position circuit controller for governing said switch machine, a remotely controlled relay, operating circuits for said two-position circuit controller governed by said remotely controlled relay, holding circuits for said two-

position circuit controller governed by said remotely controlled relay, a detector track section, means opening the operating circuits of said two-position circuit controller when said detector track section is occupied, and means effective 5 when said detector track section is occupied to prevent the operation of said remotely controlled relay which completes one said operating circuit for said two-position circuit controller.

66. In a system of the character described, a power-operated track switch, two track circuits at the switch, one in the main track and the other in the turnout track, a lock relay controlling the operation of said switch, an energizing circuit for said relay closed only when said two track circuits are shunted, and means for rendering said circuit effective to energize said relay when the switch is in the reverse position.

67. In combination, a traffic route for a railway 20 arranged into a first, a second and a third track section, a second railway intersecting the second track section of the first mentioned railway, a route locking circuit so controlled as to prevent a train on the second railway from proceeding over 25 the intersection when a train occupies the first track section; and a circuit means to release the route locking circuit by two subsequent steps, one of which is accomplished as the train in the first track section advances into the second track section, while the second step is accomplished as the 30 train advances from the second track section into the third track section.

68. In combination, a first, a second and a third track section for a railway track forming a traffic 35 route over which traffic may move in either direction, a second railway track intersecting the second track section, a route locking circuit so controlled as to prevent a train on the second railway track from proceeding over the intersection 40 when a train enters either the first or the third track section, circuit means to release the route locking circuit when a train enters the first track section and then subsequently occupies the second and third section or when a train enters the 45 third section and then subsequently occupies the second and first track section.

69. In combination, a traffic route for a railway arranged into a first, a second and a third track section, a second route having a portion common 50 with the second track section of the first mentioned route, a route locking circuit so controlled as to prevent a train on the second route from proceeding over the common portion when a train occupies the first track section; and a circuit 55 means to release the route locking circuit by two subsequent steps, one of which is accomplished as the train in the first track section advances into the second track section, while the second step is accomplished as the train advances from the second track section into the third track section.

70. In combination, a first, a second and a third track section for a railway track forming a traffic route over which traffic may move in either direction, a second railway track having a portion 65 common to the second track section, a route locking circuit so controlled as to prevent a train on the second railway track from proceeding over the common portion when a train enters either the first or the third track section, circuit means 70 to release the route locking circuit when a train enters the first track section and then subsequently occupies the second and third section or when a train enters the third section and then subsequently occupies the second and first track section.

71. Switch locking means for locking a track switch against operation comprising, a normally energized stick relay which is deenergized if a signal governing traffic over the track switch indicates clear while there is a train approaching 5 such signal, a locking circuit permitting operation of said track switch including a contact closed when said signal is at stop and said stick relay is energized, and means for restoring said stick relay if two adjacent track circuits associated with said 10 track switch are shunted simultaneously.

72. Switch locking means for locking a track switch against operation comprising, a normally energized stick relay which is deenergized if a signal governing traffic over a track switch indicates clear while there is a train approaching such signal, a locking circuit permitting operation of said track circuit including a contact closed when said signal is at stop and said stick relay is energized, and means for restoring said 20 stick relay if two adjacent track circuits associated with said track switch are shunted simultaneously and said track switch assumes the proper position.

73. In switch locking means, in combination 25 with a stretch of track, a turn-out, a switch at the turn-out, and means for operating the switch, a lock means for the switch operating means, means for making the lock means effective upon clearing a signal controlling traffic over the 30 switch, and means maintaining the lock means effective only if a train is approaching the signal at the time the signal is cleared.

74. In switch locking means, in combination with a stretch of track, a turn-out, a switch at the 35 turn-out, and means for operating the switch, a lock means for the switch operating means, means for making the lock means effective upon clearing a signal controlling traffic over the switch, and means maintaining the lock means 40 effective only if a train is approaching the signal at the time the signal is cleared, and means automatically removing the locking, and requiring the simultaneous occupancy of two adjacent track sections, provided the signal is put to stop. 45

75. In an interlocking system for railroads, a railroad track switch, means for operating said track switch, a signal governing traffic over said track switch said signal being manually operable to indicate clear or stop, approach locking means 50 preventing operation of said track switch a predetermined time after said signal is manually caused to indicate stop whenever a train is approaching said track switch, means automatically causing said signal to indicate stop upon the passage of a train over said track switch, and means rendering said approach locking means ineffective when said signal is caused to be automatically put to stop, said means being effective only until said signal is again manually governed. 55

76. In an interlocking system for railroads, a railroad track switch, means for operating said track switch, a signal governing traffic over said track switch said signal being manually operable to indicate clear or stop, approach locking means preventing operation of said track switch a predetermined time after said signal is manually caused to indicate stop whenever a train is approaching said track switch, means automatically causing said signal to indicate stop upon the passage of a train over said track switch, and means rendering said approach locking means ineffective when said signal is caused to be automatically put to stop, said means being 60 70 75

- effective until said signal is again manually governed.
77. In an interlocking system for railroads, a railroad track switch, a switch machine for operating said track switch, a signal governing traffic over said track switch said signal being manually operable to indicate clear or stop, approach locking means preventing operation of said switch machine, releasing means for releasing said approach locking means a predetermined time after said signal is manually caused to indicate stop whenever a train is approaching said track switch, means automatically causing said signal to indicate stop upon the passage of a train over said track switch, and other means for releasing said approach locking means when said signal is caused to be automatically put to stop, said other means being effective continuously until said signal is again manually governed.
78. In an interlocking system for railroads, a railroad track switch, a switch machine for operating said track switch, a free and unlockable lever for controlling said switch machine, a signal for governing traffic over said track switch said signal being manually operable to indicate clear or stop, approach locking means preventing operation of said switch machine in response to a change in the position of said lever if said signal indicates clear, releasing means for releasing said approach locking means a predetermined time after said signal is manually caused to indicate stop whenever a train is approaching said track switch, means automatically causing said signal to indicate stop upon the passage of a train over said track switch, and other means for immediately releasing said approach locking means when said signal is caused to be automatically put to stop, said other means being effective continuously until said signal is again manually governed.
79. In combination, a section of railway track including a track switch, a control relay for operating the switch, a detector track circuit for the section having a track relay, a line circuit including said control relay, manually controllable contacts located at a point remote from the switch for controlling the line circuit, means controlled by said track relay for opening the line circuit continuously as long as the detector track circuit is occupied, and means associated with said manually controllable contacts for indicating when the line circuit is open.
80. In combination, a section of railway track including a track switch, a control relay for operating the switch, a detector track circuit for the section having a track relay, manually controllable contacts located at a point remote from the switch for controlling said relay, an indication relay at said remote point, a line circuit including said control relay, said indication relay and said contacts, means controlled by said track relay for opening the line circuit continuously as long as the detector track circuit is occupied, and indication means controlled by the indication relay for indicating when said line circuit is open.
81. In combination, a section of railway track including a track switch, a control relay for operating the switch, a detector track circuit for the section having a track relay, manually controllable contacts located at a point remote from the switch for controlling said relay, an indication relay at said remote point, a line circuit including said control relay, said indication relay and said contacts, means controlled by said track relay for opening the line circuit continuously as long as the detector track circuit is occupied, other

means adjacent the switch for momentarily opening the line circuit, and means controlled by the indication relay for distinctively indicating the continuous or momentary opening of said line circuit.

5

82. In a system of approach locking for power-operated switches, the combination with a stick relay which must be energized to permit power operation of a railway track switch, of means for energizing said stick relay including a circuit closed only upon simultaneous shunting of two different but adjacent track circuits.

83. In a system of approach locking, the combination with a power-operated switch, of signals for governing traffic over said switch, a stick relay which must be energized to permit power operation of said switch, and a circuit for effecting the energization of said relay which becomes closed in response to the movement of a train past one of said signals provided two different track circuits adjacent the switch are simultaneously shunted.

84. In a system of the character described, a power-operated track switch over which traffic may move in opposite directions, a stick relay for controlling the operation of said switch, a detector track circuit, track circuits adjacent to said detector track circuit on each side thereof, two energizing circuits for said stick relay each closed when the detector track circuit and an adjacent track circuit in advance thereof are shunted, and means dependent upon the direction of train movement toward the switch for rendering one or the other of said circuits effective to control said stick relay.

85. In a system of the character described, a power-operated track switch, two track circuits at the switch, one in the main track and one in the turnout track, a relay for at times controlling the operation of said switch, an energizing circuit for said relay closed only when said two track circuits are shunted, and means for rendering said circuit effective to energize said relay when the switch is in the reverse position.

86. In a system of approach locking for a power operated track switch, the combination with a lock relay of the stick type which must be energized to permit operation of the switch, signals for governing the movement of traffic over the switch, a pickup circuit for said lock relay which becomes closed in response to the movement of a train past one of said signals provided two different track circuits adjacent the switch are simultaneously shunted, and a stick circuit for said lock relay including its own front contact and closed if said signals are at stop.

87. In a system of approach locking for a power-operated track switch, a stick relay for controlling the operation of the switch, a detector track circuit associated with the switch, two approach track circuits including one in advance and one in the rear of said detector track circuit, and two pickup circuits for said stick relay one including contacts closed when the detector track circuit and the approach track circuit in advance are simultaneously shunted and the other including contacts closed when the detector track circuit and the approach track circuit in the rear are simultaneously shunted.

88. In combination, a railway signal, an approach track circuit for said signal including a track relay, a second and a third track circuit, each of which includes a track relay, an approach locking stick relay, means for energizing said approach locking relay including a front contact of

75

said approach track relay, means for energizing said approach locking relay including a back contact of said second track relay in series with a back contact of said third track relay, and a stick 5 circuit for said approach locking relay controlled by said signal.

89. In combination, a section of railway track containing a switch, an approach section adjoining said switch section, a second approach section 10 adjoining said switch section, a signal for governing traffic movements over said switch, an approach locking relay, a circuit controlled by traffic conditions in said first approach section for controlling said relay, a second circuit controlled 15 jointly by traffic conditions in said switch section and traffic conditions in said second approach section for controlling said relay, and means controlled by said relay for controlling said switch.

90. In a system of the character described, a 20 power-operated track switch, two track circuits at the switch one in the main track and the other in the turnout track, a stick relay which must be energized to permit power operation of said track switch, a plurality of means for energizing said 25 stick relay, said means including a circuit closed only when two track circuits are shunted concurrently, and means for rendering said circuit effective to energize said stick relay only when the switch is in its turnout position.

30 91. In a system of the character described, a power-operated track switch, a detector track circuit associated with said track switch, another track circuit in a track section adjacent said detector track section, a stick lock relay which when deenergized prevents power operation of said track switch, a pickup circuit for said stick relay closed by a passing train only if both of said track 35 circuits are simultaneously occupied, and a stick circuit for said stick relay closed only if a signal for governing the movement of traffic over said 40 switch is at stop.

92. In a system of the character described, a power-operated track switch over which traffic may move in opposite directions, a stick relay, a 45 detector track circuit, track circuits adjacent to said detector track circuit on each side thereof, a pickup circuit for said relay closed when both said adjacent track circuits are unoccupied, a second pickup circuit for said relay closed when 50 the detector track circuit and one adjacent track circuit are occupied, a third pickup circuit for said relay closed when the detector track circuit and the other adjacent track circuit are occupied, a stick circuit for said relay including its own front 55 contact, and means controlled by said relay for controlling the switch.

93. In combination with a detector section of railway track including a power-operated track switch, a track circuit for said detector section 60 having a track relay, an approach section of track adjacent said detector section, signals for governing the movement of traffic over said switch, manually operable means for controlling the switch and the signals, means preventing operation of the switch when the detector section is occupied, means preventing operation of the switch when a signal has been cleared and for a predetermined time interval after a signal is restored to stop when there is a train approaching 65 within a predetermined distance of the signal, and means for automatically releasing said locking means when the detector section becomes occupied comprising a back contact of the detector track relay in series with a contact closed only when 70 said approach section is occupied.

94. In combination, a stretch of railway track including a power-operated track switch, a polarized switch control relay, a locking relay controlled in accordance with traffic conditions in said stretch, manually controllable operating circuits 5 for the control relay including front contacts of said locking relay, holding circuits for the control relay including its own polar contacts and back contacts of said locking relay, and operating circuits for the switch including front neutral and 10 polar contacts of said control relay.

95. In combination, a detector section of railway track including a power-operated track switch, a polarized switch control relay, a track relay which becomes deenergized when the detector section is occupied, manually controllable operating circuits for the control relay including front contacts of said track relay, holding circuits for the control relay including its own polar contacts and back contacts of said locking relay, 20 and operating circuits for the switch including front neutral and polar contacts of said control relay.

96. In combination, a stretch of railway track including a power-operated track switch, signals 25 for governing the movement of traffic into said stretch, a polarized switch control relay, a locking relay which becomes deenergized when any one of said signals is cleared, manually controllable operating circuits for the control relay including 30 front contacts of said locking relay, holding circuits for the control relay including its own polar contacts and back contacts of said locking relay, and operating circuits for the switch including front neutral and polar contacts of said control 35 relay.

97. In combination, a detector section of railway track including a power-operated track switch, signals for governing the movement of traffic into said section, a track relay for said detector section, a locking relay which becomes deenergized when any one of said signals is cleared, manually controllable operating circuits for the control relay including front contacts of said locking relay and of said track relay, holding circuits effective 45 to maintain said control relay energized in its last operated position when the locking relay or the track relay is deenergized, and operating circuits for the switch including front neutral and polar contacts of said control relay.

98. In combination, a detector section of railway track including a power-operated track switch, a two-position switch control relay, manually controllable means for operating said relay to normal or to reverse effective only when the detector section is unoccupied, means responsive to the occupancy of the detector section to maintain said relay energized in its last-operated position irrespective of the condition of the manually controllable means, and operating circuits for the switch rendered effective provided said relay is energized and the switch is displaced from its last operated position to operate the switch to a position corresponding to the position of said relay.

99. In combination, a detector section of railway track including a power-operated track switch, a two-position switch control relay, manually controllable means for operating said relay to normal or to reverse effective only when the detector section is unoccupied, means responsive to the occupancy of the detector section to maintain said relay energized in its last operated position irrespective of the condition of the manually controllable means, and means for operating the 70

switch to a position corresponding to the position of said relay.

100. In combination, a stretch of railway track including a power-operated track switch, a two-position switch control relay, a locking relay controlled by traffic conditions adjacent the switch, manually controllable means for operating the switch control relay to normal or to reverse effective only when the locking relay is energized, means effective when the locking relay is deenergized to maintain the switch control relay energized in its last operated position irrespective of the condition of the manually controllable means, and operating circuits for the switch rendered effective when the switch control relay is energized and the switch is displaced from its last operated position to operate the switch to a position corresponding to the position of said switch control relay.

101. In combination, a stretch of railway track including a power-operated track switch, a two-position switch control relay, a locking relay controlled by traffic conditions adjacent the switch, manually controllable means for operating the switch control relay to normal or to reverse effective only when the locking relay is energized, means effective when the locking relay is deenergized to maintain the switch control relay energized in its last operated position irrespective of the condition of the manually controllable means, and means for operating the switch to a position corresponding to the position of said switch control relay.

102. In combination, a section of railway track containing a switch, an approach section adjoining said switch section, a signal for governing the movement of traffic into said switch section, a control circuit for the signal controlled by traffic conditions in said switch section and in said approach section, a stick relay, a pickup circuit for said relay controlled by traffic conditions in said switch section and in said approach section, a stick circuit for said relay controlled by said signal, and means controlled by said stick relay for controlling said switch.

103. In combination, a stretch of railway track including a first and a second section as well as a track switch, approach locking means for at times preventing the operation of said switch when a train approaches the switch, and means controlled jointly by traffic conditions in said first section and by traffic conditions in said second section and rendered effective when both said sections are simultaneously occupied to energize said locking means, and means effective when said locking means is energized to release the switch.

104. In combination, a stretch of railway track including a first and a second section as well as a track switch, a signal for governing the movement of traffic into said stretch, locking means controlled by traffic conditions in said stretch for at times preventing operation of said switch, and

means controlled jointly by traffic conditions in said first section and in said second section and by said signal for energizing said locking means to release said switch.

105. In combination, a section of railway track including a switch, a second section adjacent said switch section, locking means for at times preventing operation of the switch, and means for releasing said locking means rendered effective if said switch section and said second section are simultaneously occupied by a train.

106. In combination, a section of railway track including a switch, a second section adjacent said switch section, locking means for at times preventing operation of said switch, and means responsive to the occupancy of the second section by a train and effective only after the train has passed the switch for releasing said locking means.

107. Switch locking means for locking a track switch against operation comprising, a normally energized stick relay which is de-energized only if a signal governing traffic over a track switch indicates clear while there is a train approaching such signal, a locking circuit permitting operation of said track switch including contacts closed only when said signal is at stop and said stick relay is energized, and means for reenergizing said stick relay rendered effective if two adjacent track circuits associated with said track switch are shunted simultaneously.

108. Switch locking means for locking a track switch against operation comprising, a normally energized stick relay which is de-energized only if a signal governing traffic over a track switch indicates clear while there is a train approaching such signal, a locking circuit permitting operation of said track switch including contacts closed when said signal is at stop and said stick relay is energized, and means for reenergizing said stick relay rendered effective if two adjacent track circuits associated with said track switch are shunted simultaneously and said track switch assumes the proper position corresponding to the said two track circuits.

109. In combination, a railway track switch having a normal and a reverse position, a normal control relay for said switch, a reverse control relay for said switch, a polarized relay, a normal control circuit for said polarized relay controlled by a front contact of said normal control relay, a reverse control circuit for said polarized relay controlled by a front contact of said reverse control relay, a stick circuit for said polarized relay including one of its own polar contacts and controlled by a back contact of said normal control relay and a back contact of said reverse control relay, and means for operating said switch to its normal or its reverse position according as said polarized relay is energized in the normal or the reverse direction.

LESTER E. SPRAY.
